UNITED STATES PATENT OFFICE

2.455.647

ENGINE CONSTRUCTION

Leslie W. Beaven, Chicago, Ill.

Original application July 29, 1942, Serial No. 452,740. Divided and this application March 12, 1944, Serial No. 529,612.

4 Claims. (Cl. 123-119)

This application is a division of application Serial No. 452,740, filed July 29, 1942, Patent 2,357,778, issued September 5, 1944.

The present invention relates, in general, to internal combustion engines, but more specifically to the general assembly of the parts of the engine structure, whereby fuel oil is employed not only as the explosive fuel, but also as a lubricant for the moving parts of the engine, as well as a coolant.

A further object is to provide, in an engine of this character, improved means whereby fuel and air may be supplied, preferably, to a pump mechanism, which latter operates to compress and transform a cold and heterogeneous mixture of air and fuel into a heated emulsion to produce a heated, finely divided and homogeneous mist or fog mixture of air and fuel, said mixture being delivered to the intake of the engine, preferably by the pump mechanism, whereby the vaporization of the fuel can be adequately assisted by the heat from the internal parts of the engine.

In the present exemplification of the invention, there is shown and described a supercharger in connection with the fuel feeding means, the specific construction of which supercharger forms the subject matter of the above referred to co-pending application, and is described herein for the purpose of a clear understanding thereof, and its connection with the present invention.

The structure here shown embodies a centrifugal air-cooled engine having the cylinders radially disposed to revolve upon a stationary shaft, and the fuel is supercharged and fed, by centrifugal force, directly through the pistons.

The fuel employed, which is preferably heavier than gasoline, is fed with air, through the main crankshaft, into the main housing of the engine, and thence through the pistons into the explosion chambers.

Owing to the fact that this fuel does not pass any of the pistons until the respective intake valve is open, the fuel will act as a lubricant upon the moving parts of the engine, tending to cool these parts, and vaporization will be assisted by the heat absorbed.

Inside the engine, due to centrifugal action of the whirling or spinning cylinders, the fuel mixture is forced against the under side of the pistons, and, when the intake valve in a piston is opened, passes through the piston and is packed with force into the combustion chamber. The engine is therefore supercharged without any special mechanism. Also, the discharge of the

exhaust gases is facilitated by the same centrifugal force, being thrown out through the exhaust ports when the valve opens, thus relieving the pistons of back pressure.

To the attainment of these ends and the accomplishment of other new and useful objects as will appear, the invention consists in the features of novelty in substantially the construction, combination and arrangement of the several parts, hereinafter more fully described and claimed and shown in the accompanying drawings illustrated in this invention in which

Figure 1 is a view partly in elevation, partly in section, and partly broken away, of an engine of this character, constructed in accordance with the principles of this invention, and illustrating one of the various radially disposed engine cylinders.

Figure 2 is a vertical sectional view taken axially through a part of the engine.

Figure 3 is an enlarged detail sectional view of the fuel feeding devices.

Figure 4 is an enlarged vertical sectional view of one of the motion transmitting pinions, with the adjacent portions of the supercharger structure.

Figure 4a is an enlarged view, partly in elevation and partly in vertical section, showing another portion of the supercharger.

Figure 5 is a face view, presented in a fragmental manner, of one of the impeller members shown in Figure 2.

Figure 6 is a view, similar to Figure 5, of another of the impeller members.

5 Figure 7 is an end elevation of an impeller fin or blade of the preferred type.

Figure 8 is a detail sectional view taken on line 9—9, Figure 2, with parts omitted.

The accompanying drawings are to be understood as being more or less diagrammatic, for the purpose of illustrating a typical or preferred embodiment of this invention.

The engine consists, essentially, of an engine shaft 10, commonly known as the crankshaft, which is stationary, and is preferably provided with an axial bore 11, through which the combustible fuel is fed to the engine casing 12, and thence to the engine cylinders 13 (only one of which is illustrated) that are disposed in radial arrangement upon the casing. The casing and cylinders are adapted to rotate upon the shaft 10, and the hub 14 of the casing is rotatably mounted in a rigid supporting frame 15, of any suitable construction. Anti-friction bearings 16 may be interposed between the engine casing hub

14 and the supporting frame 15, and similar bearings 17 are disposed between the hub 14 and the adjacent portion of the shaft 10.

The combustion fuel is adapted to pass through the bore 11 of the shaft 10 and into the engine casing 12, where it will enter the inner ends of the cylinders 13, from where it is admitted into the combustion chambers by means of suitable valved ports located in the piston's 18, which latter reciprocate in the cylinders and have their 10 pitmans operatively connected, in any suitable manner, to the crankshaft 10.

The fuel feed devices and the supercharger apparatus are enclosed within a suitable housing that is mounted, preferably, on the side of the support 15 which is opposite the engine casing 12. This housing preferably embodies a cylindrical wall or shell portion 19 having lateral lugs 20 by which it is anchored to its support, preferably by means of bolts or the like. The outer portion of said housing is closed by means of a concavo-convex end wall 21 which is preferably enlarged or thickened to provide an inwardly projecting boss 22 that has an opening 23. The shaft 10 is provided with an extension 24 that is secured within the housing in any suitable manner, such as by means of a key 25, and the opposite end of said extension shaft 24 is preferably provided with a flange 26, by means of which latter it is secured to the end of the shaft 10 through the medium of fastening bolts 27. This extension 24 constitutes a stationary or fixed shaft upon which the supercharger is mounted for rotational movement relative thereto, and said extension is provided with a bore or passage 28 that is in axial alignment with the bore or passage 11 in the shaft 10, to form a continuation of such passage.

A fuel feed device is preferably assembled upon the inner portion of the shaft 24, and the specific construction thereof forms the subject matter of my co-pending application, Serial No. 504,873, filed October 4, 1943, now Patent 2,399,783. But one form thereof is herein described, for the purpose of a clear understanding of the present invention and of the co-operation of the fuel feeding device with the other parts of mechanisms of the engine structure. This fuel feeding device embodies a fuel and air pump which whips and intimately compresses the mixture of air and fuel into a homogeneous fine-textured heated emulsion, in the form of foam, which is fed or discharged into the intake of the engine. The exemplification of this fuel feeding device includes a suitable pump chamber 29 in which meshed gears 30 revolve to rapidly and finely churn the liquid fuel received from an inlet pipe 31, and air received from the air intake 28 into an emulsion which is discharged from the pressure side of the pump into the casing 32 of a control device. This casing is hollow, and may be of any desired size and configuration, and is closed at its outer end, the other end being open and secured within an opening 33 in the shaft 24, whereby communication will be established between the casing 32 and the passage 28 in the pipe 24.

An elongated piston or plunger 34 is reciprocably mounted in the casing 32, and is of such dimensions that it substantially fills the chamber of the casing in both longitudinal and transverse directions. This piston is provided with a reduced or shouldered portion 35 midway of the length thereof, that is in registration with an annular channel 36 extending around the bore of the casing, to provide a space that receives a dis-

15 persion of air and fuel through a passageway 37, which latter communicates with the pressure side of the pump.

A spray port 38 is provided in the upper end of the piston or plunger 34, that is controlled by a spray valve 39 adapted to be actuated by the pressure of the fuel received from the pump, which fuel is transmitted to the valve 39 through a longitudinal passage 39a in the adjacent section of the piston body between the shouldered portion 35 and the chamber in which the spray valve is reciprocably and yieldably mounted, the tendency of the fuel pressure to open the spray port 38 being opposed by the spring 38a behind the spray valve 39.

The dispersion of air and fuel is created within the pump 29, said fuel being first received thru the fuel line 31 and driven by the pump gears 30 thru port 37 to the annular chamber 36 where its entrapment causes the pressure to rise against the spray valve 39. But the piston 34 is differential due to a greater diameter above its waist than below it, whereby the shouldered portion 35 becomes the unbalanced and effective piston area exposed to the pressure in chamber 36 and said piston 34 rises against the resistance of the spring 38 until the by-pass channel 32c relieves the hydraulic pressure. This by-pass channel 32c, 20 consists of three connected parts, an upper horizontal passage indicated by the small dotted circle in piston 34 below its waist, a vertical passage also in said piston and a lower horizontal run which is partly in the casing 32 and partly in the piston 34; and connects the passage 32b in the casing 32, to passage 32d, when the pump is 25 in operation and the piston has been lifted off its seat in the bottom of the case 32, thereby also permitting by-passed fuel to return to the intake side of the pump and be recirculated. The lower horizontal run of passage 32c forms a control 30 valve between the case 32 and the piston 34 which functions to regulate the amount of air admitted to be mixed with the fuel to form the emulsion, said air being admitted thereto from the intake 35 passage 28 in shaft 24 via passage 32a, which is a clearance between piston 34 and the case 32, thence via the passage 32b in the case. In operation, this control valve is open when the oil by-pass channel 32c is closed at its upper ends and 40 is closing when the by-pass is opening its upper horizontal run into communication with chamber 36, so the amount of air admitted thru the air control valve is approximately in inverse proportion to the amount of flow in the by-pass 45 channels 32c. This is the result desired, since it makes the amount of air admitted about equal to the amount escaping in the emulsion at the spray port 38, thereby keeping the mixture of air and oil which issues as a dispersion at the spray port 38 always homogeneous. The flow in the by-pass 32c is the complement of the flow thru the spray port 38. Another feature of the fuel feed 50 control makes the by-passing, and thereby the feeding function, responsive to the density of the air in the intake passage 28, a lessened air density decreasing the fuel feed by increasing the by-pass, and an increased air density increasing the fuel feed by decreasing the by-pass.

The upper end of the piston 34 is exposed to, 55 and is affected by, any variations of air-pressure changes which occur in the passageway or bore 28 of the extension shaft 24. The shaft 40 of one of the pump gears projects beyond the pump chamber wall, and has secured to it a pinion 41 which meshes with an internal annular gear 42

secured to the adjacent end face of the engine casing hub 14, so that said internal gear 42 will be rotated with the engine when the latter is in operation, with the engine casing 12 and its cylinders 13 rotating upon the stationary shaft 10. This internal gear 42 is preferably mounted upon the inner face of a cylindrical frame or fitting 43, and this fitting is provided with flanges 44-45, one of which flanges is anchored to the hub 14 of the engine casing.

An annular air inlet opening 46 may be provided in the outer end portion of the shell 19, the edges of such openings having seats 47 to receive an annular filter pad or member 42a, of any suitable construction, for the purpose of filtering the air that is admitted through said opening. Said inlet opening 46 may be reinforced by suitable stays or ribs 49, which ribs also serve to prevent the filter pad 42a from being sucked or drawn into the shell by the passage of air inwardly through the opening 46.

Within the shell there is provided an internal ring gear 50 suitably supported and secured thereto, preferably by means of keys 51, said ring gear constituting one of the members of a suitable gear train employed to drive the impeller members of a supercharger. A plurality of planetary gears 52 (preferably three or more), in mesh with the internal ring gear 50, are mounted upon spindles 53 that are preferably elongated to pass through the flanges 44-45 of the frame 43 that rotates with the engine casing. The central or sun gear 55 of the planetary gear train is mounted upon the stationary shaft extension 24, and is in mesh with the planetary gears 52. A thrust-bearing or annular stop 56 may be provided to prevent movement of the sun gear 55 in an inward direction. This gear 55 may be provided with a clutch disc 57 that in turn is provided with a friction ring 58, of any suitable substance, for engagement with an opposing clutch disc 59 secured to an impeller member 60 of a supercharger.

The supercharger also embodies an impeller member 61 which confronts the impeller member 60 and is yieldably urged toward the latter, so that the elements of the clutch will normally be frictionally engaged to rotate the impellers 60-61 upon the shaft 24, through the medium of the planetary gear train, when the engine is being rotated upon its shaft 10. The impeller members 60-61 are rotated in opposite directions so that the required amount of compression is secured at one-half the speed otherwise required.

The impellers preferably comprise circular plates 60 and 61 having concentric rows of arcuate blades or fins 60a and 61a, respectively, the said rows on one plate (60) being disposed in alternate arrangement with respect to the rows of blades on the confronting plate 61, and in order to accomplish this arrangement, the rows on each plate are separated from each other by channels or grooves 60b and 61b that are each of proper width and depth to intimately accommodate the opposing rows of blades with close clearances between the parts. As shown in Figure 2, the clearances between the interfitting elements have been intentionally exaggerated, for the purpose of avoiding confusion in the drawings.

The blades are of segmental or arcuate cross-section, preferably of an aerofoil section, such as illustrated in detail in Figure 8 of the drawings, wherein it will be observed that the trailing por-

tions of the blades curve inwardly and are closer to the rotational axis of the impeller than are the leading edges which plow or cut into the air in the manner of the wings of an airplane. The individual blades are spaced apart from each other the proper distances, to permit the air to readily pass between them, and, since the confronting impellers rotate in directions opposed to each other, the air is forced in a somewhat zigzag or back-and-forth course toward the axis of rotation of the impellers, thus creating centripetal force as distinguished from the centrifugal principle upon which it has heretofore been customary to operate supercharger devices. The opposed directions of rotation renders it possible to revolve the impellers at a relatively slow speed as compared with the high speed at which superchargers have heretofore been rotated.

The impeller members 60 and 61 are provided with axial openings whereby they may be mounted for rotation upon the shaft 24, and around these openings there are provided facing recesses 60c and 61c, which together provide an annular central chamber 62 adjacent the shaft 24, to receive the compressed air that has been driven centripetally inwardly by the blades of the impellers, and also to provide for the mounting of motion transmitting devices which are operable between the impellers. Toothed annular racks 63a and 63b are formed upon the impeller members 60 and 61, respectively, which racks extend around the margins of the central chamber 62 and confront each other in spaced relation.

A ring-shaped spider 64 surrounds the shaft 24, to which it is slidably secured by a key 65 to prevent rotation of the spider ring. A plurality of radially disposed beveled pinions 66 are carried by the ring 64 and are in mesh with the teeth of the racks 63a and 63b, the pinions being rotatably mounted upon the smooth shanks of radially disposed bolts 67 that are screwed into the body of the spider 64. The spider ring 64 is provided with slots 64a which extend between the pinions 66 and insure passage of the centripetally driven air current to the chamber 62. The surfaces of the impeller members 60 and 61 upon each side of the annular racks 63a and 63b are tapered inwardly toward each other, as shown at X in Figure 4, and the inner and outer end portions 68-69 of the pinions are smooth and correspondingly tapered, thus providing a means to limit the nearness of the impellers 60-61 to each other.

The impeller member 61 is urged toward the impeller 60 in any suitable manner, but preferably by means of a disc 73 mounted upon threads 72 on the boss 22. The peripheral edge of this disc is provided with teeth 74 with which a pinion 15 meshes. This pinion may be rotated by means of a grip portion 77 secured to the shaft 76 of the pinion. A spring 78 is disposed between the disc 73 and the hub of the impeller member 61, and, if desired, a ball bearing member 79 may be interposed between the end of the spring and the hub of the impeller 61.

By means of this structure it will be obvious that whenever the engine is rotating, the movement thereof will be transmitted through the planetary gear train and the clutch to the impeller member 60, thence through the rack 63a and the beveled pinions 66 to rack 63b, thereby moving the other impeller member 61 in a direction opposed to the direction of movement of the confronting impeller member 60.

The innermost row of impeller blades, in which the curvature of the blades is substantially the same as those of the other blades, may have a tendency to spin the air into a whirlpool, creating centrifugal force opposing the centripetal force that has been created by the device, and in order to resist this tendency and to continue to force the air in an inwardly radial path, there is provided suitable means adjacent said innermost row of impeller blades for preventing a circular path of the air and thus continuing the centripetal force which has been created. These means are termed a drift baffle, which embodies a stationary annulus or ring 70 which is provided with lugs 70a secured to the spider 64 through the medium of bolts 67. Arcuate baffles 71 are provided on this ring or annulus 70, which curve somewhat sharply inwardly toward the axis of the supercharger at a different tangent than the blades of the impellers 60-61, and in opposite directions thereto.

In order to accommodate this drift baffle, the innermost channel or groove of the impeller 60 is made wider, as at y, opposite the innermost channel or groove of the confronting impeller 61, thus providing an annular recess in which said drift baffle is disposed.

The shaft 24 is provided with openings 80 forming communication between the passage 28 and the chamber 62, thus allowing the centripetally compressed air to discharge into the passage 28. The throttle for controlling the discharge of air through the openings 80 is preferably tubular, as shown at 81, and fits snugly into the passage 28, but is adapted to be rotated therein by means of a handle or lever 82 secured thereto. Slots 83 are made in the wall of the throttle, which may be moved into or out of register with the openings 80, and the end of the throttle may be closed by a wall 84, the throttle being held in position by means of a suitable member 85.

Above the fuel feed device and spray port, there is provided a dome 86 (see particularly Figure 39) which houses a coiled expansion spring 87, the tension of which is adapted to be adjusted, and which has its lower end engaging a follower disc 88 in the lower end of the dome. This spring is for the purpose of exerting pressure upon the piston or plunger 34 of the fuel feed device. The pressure of the spring is transmitted, preferably, through the medium of a toggle device 89, the ends of which device respectively engage the follower 88 and the upper end of the piston or plunger 34. The intermediate hinged portions of the toggle are provided with right and left-hand threaded nuts 90 that are respectively engaged by the correspondingly threaded portions of a feed screw 91 that extends through the outer end of the throttle member 81 and the retainer cup 85, where it is provided with a knob or button 92 for operating it. Rotation of the feed screw 91 will further separate, or draw closer together, the nuts 90 at the intermediate hinges of the toggle, and thus control the tension of the spring 87, to control the flow of fuel through the spray port 38 into the path of the compressed air current which is moving past the spray port in transit to the engine casing and cylinders.

With this improved construction it will be manifest that there is provided means whereby low-grade oils, and oils or fuel other than gasoline, may be employed in the operation of the engine, the oil being broken up and mixed with the air to form in the pump, a heated emulsion,

being subsequently delivered to the intake pipe 28, where it is converted into the form of a mist and then delivered to the combustion chambers of the cylinders. Furthermore, the fuel which is employed in the formation of the emulsion not only serves as the explosive medium for driving the engine, but also lubricates the moving parts of the engine on its passage to the combustion chambers, thereby dispensing with the necessity of using, as is the case with the engines now employed, two separate liquids; one for the explosion and the other for lubrication.

Furthermore, with the present construction, all mechanism for providing a forced feed lubrication, in addition to the mechanism for supplying the fuel to the combustion chambers, will be dispensed with, as the same mechanism which supplies the fuel to the combustion chambers will, in the present invention, also serve as a means for effecting lubrication of the moving parts of the engine.

While the preferred embodiment of the present invention has been herein shown and described, it is to be understood that various changes may be made in the details of construction and in the combination and arrangement of the several parts, within the scope of the claims, without departing from the spirit of this invention.

What is claimed as new is:

1. An internal combustion engine embodying a hollow shaft, about which the engine casing and cylinders revolve, a stationary housing adjacent the engine casing concentric to said shaft, a hollow extension forming a continuation of said shaft, said extension provided with a series of transverse apertures, the bores of said shaft and said extension constituting a fuel passageway discharging into the engine casing, an impeller in the housing and rotatably mounted on said extension, adapted to centripetally create air-pressure and discharge the same through said apertures into said passageway and thence into the engine casing, means also in the housing for feeding fuel and air mixture into said passageway, a driving connection between the rotatable engine casing and the said impeller, a clutch included in said connection, and yielding means tending normally to render said impeller active with respect to said clutch, said connection, clutch and yielding means being disposed within the housing.

2. In an engine, a stationary shaft, cylinders rotatable about the shaft, there being a passage in the shaft in communication with the cylinders, a housing supported by the engine and into which housing the shaft extends, a supercharger disposed in said housing and rotatable about said shaft, means also within the housing and disposed intermediate the supercharger and the cylinders for receiving liquid fuel and also for receiving air from said supercharger, said means operating to form a heated emulsion of said air and fuel received thereby and also operating to discharge said heated emulsion into said passage for transmission to the engine cylinders, and means responsive to the rotation of said cylinders for operating the last said means and the said supercharger.

3. In an engine, a stationary shaft, cylinders rotatable about the shaft, there being a passage in the shaft in communication with the cylinders, a housing supported by the engine and into which housing the shaft extends, a supercharger disposed in said housing and rotatable about said shaft, means also within the housing and dis-

posed intermediate the supercharger and the cylinders for receiving liquid fuel and also for receiving air from said supercharger, said means operating to form a heated emulsion of said air and fuel received thereby and also operating to discharge said heated emulsion into said passage for transmission to the engine cylinders, means responsive to the rotation of said cylinders for operating the last said means and the said supercharger, and means for controlling, at will, the supply of air from said supercharger to the engine cylinders.

4. In an engine, a stationary shaft, cylinders rotatable about the shaft, there being a passage in the shaft in communication with the cylinders, a housing supported by the engine and into which housing the shaft extends, a supercharger disposed in said housing and rotatable about said shaft, means also within the housing and disposed intermediate the supercharger and the cylinders for receiving liquid fuel and also for receiving air from said supercharger, said means operating to form a heated emulsion of said air and fuel received thereby and also operating to discharge said heated emulsion into said passage for transmission to the engine cylinders, and means responsive to the rotation of said cylinders for operating the last said means and the said supercharger, the last said means embodying a driving connection with the engine cylinders and

also a driving connection between the engine cylinders and the supercharger for operating them.
